UNITED STATES PATENT OFFICE.

DAMASE JACQUES, OF DETROIT, MICHIGAN.

WINCH.

Application filed August 28, 1923. Serial No. 659,067.

To all whom it may concern:

Be it known that I, DAMASE JACQUES, a citizen of the United States of America, residing at Detroit, in the county of Wayne 5 and State of Michigan, have invented certain new and useful Improvements in Winches, of which the following is a specification, reference being had therein to the accompanying drawings.

10 In my Patent No. 1,059,998, granted April 29, 1913, there is disclosed a single winch that may be advantageously used in connection with a davit and the winch embodies novel means whereby one person may 15 handle one end of a boat for lowering away or bringing on board, the controlling means of the winch being arranged to insure safety as well as ease of control.

19 In my Patent No. 1,125,107, granted Jan. 20, 1915, there is disclosed a somewhat similar davit winch wherein the winch and its operating handle include a braking device.

25 This invention aims to improve my former winches in certain particulars, which may be characterized as follows;

First, I provide a double winch which may be operated as a single winch or individual winding drums thereof independently operated and controlled. Such a winch 30 may be located to serve two davits and a single boat or two davits in proximity to each other controlling adjacent ends of two boats.

Second, I provide a double winch with a single main brake by which two winding drums may be controlled, and individual brakes by which either winding drum may be controlled.

Third, my winch includes a novel clutch 40 mechanism that may be easily operated to permit winding drums to be used independent of each other.

Fourth, the double winch is constructed with a view to reducing the cost of manufacture and at the same time retain those features by which safety, durability, compactness and ease of control are secured. With such ends in view my invention re-

sides in the novel construction to be herein-after described and then claimed, and reference will now be had to the drawings, wherein—

Figure 1 is a front elevation of the winch; Fig. 2 is a plan of the same;

Fig. 3 is a view of one end of the winch; Fig. 4 is a longitudinal sectional view taken on the line IV—IV of Fig. 3;

Fig. 5 is an enlarged longitudinal sectional view taken on the line V—V of Fig. 1;

Fig. 6 is an enlarged cross sectional view 60 taken on the line VI—VI of Fig. 1, and

Fig. 7 is a cross sectional view taken on the line VII—VII of Fig. 5.

The winch comprises a substantial framework that may be mounted on the deck of 65 a vessel, attached to a davit, or secured to any suitable support and the framework, as shown, includes end frames 1 and 2 connected by longitudinal frames 3 and 4 and tie rods 5 and 6. The end frames 1 and 2 may 70 be provided with feet or flanges 7 so that the winch framework may be secured to a floor or other support.

Connecting the end frames 1 and 2 is an arbor or shaft 8 and rotatable on the arbor 75 or shaft are two main drums 9 and 10, each having peripheral end flanges or heads 11 and 12 with the heads 12 confronting each other and provided with convex faces 13 forming an annular groove or shoeway 80 which in cross section tapers inwardly from the peripheral edges of the heads 12 to approximately the axis of the drums.

Riveted or otherwise secured to the heads 11 are gear wheels or rims 14 by which main 85 drums 9 and 10 may be independently rotated.

On the frame 3 is a bracket 15 and pivotally connected to the upper end of said bracket is a curved brake lever or shoe 16 90 extending over and between the heads 12 of the two main drums 9 and 10. On the free end of the lever or shoe 16 is a pad 17 which may be pressed, by hand or foot, to wedge the lever or shoe between the drum 95 heads 12 and retard, if not eventually stop

rotation of either the drums 9 or 10, when one or the other of said drums is otherwise held stationary, or both of said drums.

The frames 1 and 2, in a plane above the winding drums, are provided with openings 5 for bearings 18 and 19 which are suitably secured to said end frames, and journaled in the bearing 18 is a long sleeve 20 in which is mounted a short shaft 21.

10 Journaled in the bearing 19 is a long shaft 22 which has a reduced end 23 extending into the long sleeve 20 contiguous to the end of the short shaft 21 in said sleeve, such shaft alignment in the sleeve insuring a rigid structure from one end frame to the other.

15 On the outer ends of the shafts 21 and 22 are conical wheels 24 provided with contractible bands 25 having cranks 26 and screws 27, said screws being used to contract the bands 25 about the conical wheels 24, for a braking action, when the cranks 26 bear against pivoted brackets 28 carried by the end frames 1 and 2. The pivoted brackets 25 28 may be swung to inactive positions to provide clearance for the cranks 26 when using either crank to rotate either of the shafts 21 or 22. The pivoted brackets may be swung to active positions, as best shown 30 in Fig. 1, so that the cranks may rest thereon and remain stationary while the screws 27 are manipulated for braking purposes in connection with either of the shafts 21 or 22. The contractible bands 25 are retained in 35 place by retaining members 29 mounted on the ends of the shafts 21 and 22, and this individual control of either of the shafts is suggested in my prior Patent No. 1,125,107, above referred to.

40 Keyed or otherwise fixed on the long sleeve 20, adjacent the end frame 1, is a pinion 30 meshing with the gear wheel 14 of the drum 9 and pinned or otherwise fixed to the sleeve 20 and the short shaft 21, as at 31, is an auxiliary drum 32 abutting the pinion 30.

45 Mounted on the long shaft 22, adjacent the end frame 2 is a pinion 33 meshing with the gear wheel 14 of the drum 9 and abutting the pinion 33 is an auxiliary drum 34 which 50 may be held on the long shaft 22 by a spline 35 or such means as retains the pinion 33 on the long shaft.

55 The tie rods 5 and 6 are connected by a cross member 36 provided with a bearing 37 in which slides a clutch member 38 provided with a peripheral groove 39 for the inner end 40 of a shift lever 41, said lever being pivotally mounted on a depending bearing 42 carried by one end of the cross member 36. The inner end of the shift lever 41 extends through an opening 43 in the bearing 37 and oscillation of the outer end of the lever 41 reciprocates the clutch member 38 in the bearing 37. The clutch member 38 is 60 of greater length than the bearing 37 and

65 sleeved loosely on the ends of the clutch member are tubular casings 44 which have the outer ends thereof loose on heads 45 of the auxiliary drums 32 and 34. As a matter of good construction the auxiliary drum 34 70 may be pinned, as at 45a, to the long shaft 22, and the auxiliary drum 32 may be keyed or otherwise fixed, as at 46 to the sleeve 20.

75 In the clutch member 38 on the sleeve 20 is a bushing 47 and abutting the ends of said bushing are yieldable clutch members 48 and 49 housed by the tubular casings 44. The clutch member 48 is slidably keyed on the long shaft 22, as at 50, and is constantly pressed towards the clutch member 38 by the expansive force of a coiled spring 51 in the casing 44 about the long shaft 22.

80 The clutch member 49 is slidably keyed, as at 52 on the sleeve 20 and is constantly pressed towards the clutch member 38 by the expansive force of the coiled spring 53 in the casing 44 about the sleeve 20. The confronting ends of the clutch members 38, 48 and 49 have teeth or projections 54 adapted to mesh or interlock so that a driving relation may be established between all of said clutch members or the clutch member 38 with either of the clutch members 48 or 49.

85 On the inner walls of the end frames 1 and 2 are pivoted gravity pawls 54 adapted to engage the gear wheels 14 of the drums 9 and 10 and prevent clockwise rotation of 90 said gear wheels when viewing either Fig. 3 or Fig. 6.

95 There are various ways of using the winch and its use depends more or less on its installation, but in operation the following may be accomplished.

100 With the contractible bands 25 clamped on the conical wheels 24 either of the cranks 26 or both can be used for revolving the drums 9 and 10 to wind or unwind any cable or flexible member attached to said drums.

105 By loosening one of the contractible bands 25 and shifting the clutch member 38 the other crank can be used to rotate one of the drums independent of the other.

110 During the operation of either one or both of the drums rotation thereof can be controlled by the brake lever 16.

115 Rotation of either one of the drums or both may be controlled from a station, remote from the winch, by any flexible member attached to one of the tie rods 5 or 6 and wound about either of the auxiliary drums 32 or 34, as brought out or suggested in my prior Patent No. 1,059,998 previously referred to.

120 From the foregoing it will be observed that I have devised a winch having drums that may be operated in synchronism or may be individually operated from either end of the winch, and that there is a clutch mechanism, and a brake mechanism common to both drums and compactly assembled rela- 125

tive thereto which permits of the winch being easily controlled.

What I claim is:—

1. A winch comprising a frame work, 5 drums in said frame work, said drums having confronting braking heads, a driving mechanism for said drums, said driving mechanism including independent shafts and a clutch mechanism by which said shafts 10 may be operated in synchronism, and a brake lever operable between said drum heads and adapted to contact therewith.

2. A winch having drums operable in synchronism or one independent of the other, 15 a driving mechanism for said drums, said driving mechanism including independent shafts, a clutch mechanism normally coupling said shafts for operation in synchronism and adapted to permit of either shaft 20 being driven independent of the other, and auxiliary drums operated by said driving mechanism and adapted to facilitate manual control of each shaft.

3. In a winch having a winding mechanism composed of main drums operable in synchronism or independent of each other, a driving mechanism therefor including aligned 25

shafts each adapted to drive a drum, a crank for each shaft adapted to be fixed relative to its shaft and adapted to be used as a brake 30 for said shaft, and a clutch mechanism associated with said shafts whereby said shafts may be clutched together or disconnected.

4. A winch as called for in claim 3, where- 35 in said clutch mechanism includes a shiftable clutch member, yieldable clutch members and a casing for all of said clutch members.

5. A winch as called for in claim 3, and an auxiliary drum for each main drum to facilitate manual independent control of said 40 main drums.

6. In a winch, coaxial drums having confronting convex heads, a brake lever operable between the heads of said drums to control the rotation of both of said drums or 45 either of said drums when one or the other is held stationary, and a driving mechanism for said drums.

7. A winch as called for in claim 6, where- 50 in said driving mechanism includes a shaft for each drum, and means by which said shafts may be operatively coupled thereto.

In testimony whereof I affix my signature.
DAMASE JACQUES.
